UNITED STATES PATENT OFFICE

138,311

DESIGN FOR A MINIATURE ENGINE

Thomas R. Arden, Danbury, Conn., assignor to
Bard-Parker Company, Inc., Danbury, Conn., a
corporation of New York

Application December 10, 1943, Serial No. 111,983

Term of patent 14 years

(Cl. D71—1)

To all whom it may concern:

Be it known that I, Thomas R. Arden, a citizen of the United States, residing at R. F. D. No. 2, Danbury, in the county of Fairfield and State of Connecticut, have invented a new, original, and ornamental Design for a Miniature Engine, of which the following is a specification, reference being had to the accompanying drawing, forming a part thereof.

Figure 1 is a side elevational view of a miniature engine showing my new design.

Figure 2 is a front elevational view.

Figure 3 is a top plan view.

Figure 4 is a bottom plan view.

Figure 5 is a side perspective view on a somewhat enlarged scale.

The dominant features of the design reside in the portions shown in full lines.

I claim:

The ornamental design for a miniature engine, as shown and described.

THOMAS R. ARDEN.
